UNITED STATES PATENT OFFICE

EMILE CHARLES LEMOINE, OF SARATOGA, WYOMING

LAMB CASTRATOR

Application filed June 22, 1929. Serial No. 372,903.

The present invention relates to a castrator particularly designed for castrating lambs, and has for its prime object to provide a device which may be conveniently held in the hand and enable the operator to properly grip the scrotum or bag for cutting the same, and also allow the operator to grab the testicles after the cutting operation so that they may be pulled out.

10 Another very important object of the invention resides in the provision of a tool of this nature which is exceedingly simple in its construction, comparatively inexpensive to manufacture, strong and durable, easy to manipulate, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

25 In the drawings:

Figure 1 is a perspective view of the castrator showing the same in the hand of an operator.

Figure 2 is a front elevation thereof.

30 Figure 3 is a side elevation thereof.

Figure 4 is a top plan view thereof.

Figure 5 is a vertical section therethrough, and,

35 Figure 6 is a perspective view showing the upper end of the handle.

Referring to the drawing in detail it will be seen that the numeral 5 denotes an elongated tubular handle, somewhat oblong in cross section, and having at its upper end on one side, a relatively large opening 6, the bottom end of which is formed with notches 7 and 8. A slot 9 is formed in the opposite side of the upper end so that a strap 10 may be engaged therein. A buckle 11 is engaged with a cap 12 at the lower end of the handle so that the strap may be engaged with the buckle as is clearly indicated in the drawing.

40 A pair of jaws 15 and 16 extend through the opening 6 having their lower edges in the notches 8 and 7 respectively. The inner ends

of these jaws are formed with apertured lugs 17 rockable on a bolt 18 having its head 19 at the upper end and its lower end extending through the cap 12 and threaded to receive an exteriorly disposed nut 20, which may be tightened to hold the jaws in place with the lower edges in the limiting slots 7 and 8.

It will be noted that the jaw 15 is slightly longer than the jaw 16. Both jaws are provided at their outer free edges with inturned edges 21 and 22 respectively. A spring 23 is coiled about bolt 18 and has end extensions 24 engaging the inner surfaces of the jaws 15 and 16 to normally hold them spread apart.

55 This castrator is held in the right hand with the thumb and two fingers on the jaws 16 and 15 respectively, the thumb being located downwardly while the device is being used. The strap is placed across the back of the hand just back of the knuckle. The two fingers on the upper jaw 15 and the thumb on the lower jaw will operate the castrator by pressing and releasing the fingers. With the castrator in the right hand the operator 60 uses the knife in the left hand. The lamb's scrotum or bag is grabbed with the castrator and the end cut off with a knife and then the thumb and forefingers of the left hand presses down on the lamb's bag to force the 65 testicles out and then the testicles are grabbed with the castrator and pulled out.

70 It is thought that the construction, operation, and advantages of this invention will now be quite apparent to those skilled in this art without a more detailed description thereof. The present embodiment of the invention has been disclosed in considerable detail merely for the purposes of exemplification since in actual practice it attains the features 75 of advantage enumerated as desirable in the statement of the invention and the above description. It will be apparent that changes in the details of construction, and in the combination and arrangement of parts may be 80 resorted to without departing from the spirit or scope of the invention as hereinafter claimed or sacrificing any of its advantages.

Having thus described my invention, what I claim as new is:

1. A castrating tool of the class described comprising an elongated tubular handle having a side opening in its upper end, a pair of jaws extending through the opening, means for pivoting the inner ends of the jaws in the handle, spring means for normally holding the outer ends of the jaws apart.
2. A castrating tool of the class described comprising an elongated tubular handle having a side opening in its upper end, a pair of jaws extending through the opening, means for pivoting the inner ends of the jaws in the handle, spring means for normally holding the outer ends of the jaws apart, said outer ends of the jaws having inturned edges.
3. A castrating tool of the class described comprising an elongated tubular handle having a side opening in its upper end, a pair of jaws extending through the opening, means for pivoting the inner ends of the jaws in the handle, spring means for normally holding the outer ends of the jaws apart, said outer ends of the jaws having inturned edges, the bottom edge of the opening being provided with notches to receive the lower edges of the jaws.
4. A castrating tool of the class described comprising an elongated tubular handle having a side opening in its upper end, a pair of jaws extending through the opening, means for pivoting the inner ends of the jaws in the handle, spring means for normally holding the outer ends of the jaws apart, said outer ends of the jaws having inturned edges, the bottom edge of the opening being provided with notches to receive the lower edges of the jaws, said pivot means comprising a bolt extending through apertured lugs on the inner ends of the jaws.

40 In testimony whereof I affix my signature.
EMILE CHARLES LEMOINE.
